CLAIM

The ornamental design for a pathogen containment device as shown and described.

DESCRIPTION

FIG. 1 is a top-left front view of the pathogen containment device.

FIG. 2 is a bottom-left rear view of the pathogen containment device.

FIG. 3 is a front view of the pathogen containment device.

FIG. 4 is a rear view of the pathogen containment device.

FIG. 5 is a top view of the pathogen containment device.

FIG. 6 is a bottom view of the pathogen containment device.

FIG. 7 is a left side view of the pathogen containment device.

FIG. 8 is a right side view of the pathogen containment device.

FIG. 9 is a full section as taken along line 9-9 of FIG. 4; and, FIG. 10 is an enlarged fragmentary view of area 10 as shown in FIG. 9.

The broken lines illustrate portions of the article that form no part of the claimed design. In addition, the dot-dot-dash broken lines illustrate enlarged portions of the design.

1 Claim, 9 Drawing Sheets
